UNITED STATES PATENT OFFICE.

LOUIS CARL HENRY MENSING, OF LONDON, ENGLAND.

ELECTRIC-ARC LAMP.

SPECIFICATION forming part of Letters Patent No. 712,947, dated November 4, 1902.

Application filed June 30, 1902. Serial No. 113,836. (No model.)

To all whom it may concern:

Be it known that I, LOUIS CARL HENRY MENSING, a subject of the King of England, residing at 11 Queen Victoria street, London, England, have invented certain new and useful Improvements in Inclosed or Open Electric-Arc Lamps, of which the following is a specification.

The object of this invention is to construct 10 braking and regulating appliances for inclosed (or incandescent arc) or open electric arc lamps in such a manner that the arc may be struck and maintained in a positive and efficient manner at all times.

15 My invention will be clearly understood from the following description, aided by the accompanying drawings, in which—

Figure 1 is an elevation of sufficient of an electric-arc lamp to show my braking and 20 regulating appliance. Fig. 2 is a front elevation and plan of the brake-wheel. Fig. 3 is a front elevation and plan of the plate having two of the gripping devices. Fig. 4 is a side elevation and plan of the plate which fits 25 loosely in the plate shown at Fig. 3. Fig. 5 is a section through lines *a a* of Fig. 1. Fig. 6 is a section through line *b b* of Fig. 1. Fig. 7 shows side and front elevations of the rod carrying the snug for actuating the plates and 30 brake-wheel. Fig. 8 is a section of a globe and lower portion of a lamp.

For the purpose of my invention I journal 35 the brake-wheel 1 or wheels 2 on an axle fitted to one or more standards 3 and secure a plate 4 at one or both sides of said wheel, this plate 4 having arms 5 6 projecting over the periphery of the brake-wheel 1, one, two, or more, 6, being on one side and of a plain character, while the arm 5 on the other side 40 carries a loose-fitting plate 7, and also has hinged to it one end of a rod 8, which end carries a snug or projecting portion 9, having action upon the loose-fitting plate 7 or on the brake wheel or wheels 1 direct. The rod 8 45 is screw-threaded and adjustably connected to the actuating-lever 10, which is operated by the solenoid 11, so that when the solenoid 11 is moved by the rise or fall of the current it will through its lever 10 actuate the threaded 50 rod 8, and consequently the snug or projection 9, which will release the brake-wheel

1, or by action on the loose plate 7 push the loose plate 7 onto the periphery of the brake wheel or wheels 1 and at the same time will draw the plate 4 for the arms 6 to engage the 55 brake-wheel 1 at the opposite side, the plate being slotted for the purpose, so that all three or more grip the brake-wheel 1 as a clutch and hold it firmly, the rocking motion given by the downward movement of the threaded 60 rod 8 moving the brake-wheel 1 around to establish the arc or to feed the carbons 12 13 together whenever the resistance of the arc increases.

By making the rod 8 adjustable as to length 65 the degree of grip of the clutch can be determined, and consequently the length of the arc controlled accordingly, the movement of the carbons 12 13 being regulated by the clutch acting as a brake.

The lever 10, connecting the solenoid 11 with the threaded rod 8, is pivoted on the arms 3 and carries a weight 14, adjustable along its length, to balance the mechanism and insure prompt action and a positive downward movement of the solenoid, the weight 70 being fixed in position by the screws 15.

When the appliances are employed in a closed (or incandescent arc) or open electric arc lamp, the glass cylinder 15 can be secured 75 to the framework 16 of the lamp and the top be provided with an asbestos packing 17, clamped in the metallic cover 18 and so made that a nearly air-tight joint is made when the upper carbon 12 is situate through the hole 80 in the cover 18, the bottom of the cylinder 15 being tightly socketed in a piece 19, which carries the carbon 13.

Instead of the adjustable threaded rod 8 being connected to the solenoid by a rocking 90 arm 10 it may be connected direct, and the brake-wheel 1 may be reversed in its movement, or the snugs or projections 9 may be so arranged that the brake-wheel 1 may be caused to travel in either direction.

As will be understood, the carbon-holding cords 20 21 pass down the tubes 26 27 and are secured to the brake-wheel, one in each groove 22 23, but wrapped in reverse direction, so that on the movement of the wheel 1 95 one cord will be given off while the other is taken in, so that the carbons are moved to

and from each other; but in some cases one carbon may be a fixture.

24 is a balance-weight fitted on the rod 25 to counterbalance the weight 14.

5 What I claim, and desire to secure by Letters Patent, is—

1. In electric-arc lamps, the brake-wheel 1 carried in standards 3 and having connected therewith a plate 4 provided with arms 5 6 10 reaching over the periphery of said brake-wheel 1, loose plate 7 arranged between the arms 5 and brake-wheel 1 adjustable rod 8 pivoted to arm 5 and carrying a snug or snugs 9 for actuating the plates 4 and 7 to grip the 15 wheel 1, pivoted lever 10 connecting the adjustable rod 8 with the solenoid 11 to allow the movement of the solenoid to communicate its motion to the brake-wheel 1 for actuating

the carbons all arranged and operating substantially as and for the purpose set forth. 20

2. In electric-arc lamps a brake-wheel 1 provided with a sliding plate 4 having arms 5 6 projecting over the periphery of the brake-wheel 1, loose plates 7 situate between the arm 5 and brake-wheel 1, adjustable rod 8 25 pivoted to arm 5, snug or snugs 9 projecting from rod 8 all arranged and acting substantially as and in the manner set forth for the purpose described.

In testimony whereof I have hereunto set 30 my hand in presence of two subscribing witnesses.

LOUIS CARL HENRY MENSING.
